LABELING MECHANISM

George W. von Hofe, Bound Brook, N. J., assignor
to New Jersey Machine Corporation, Hoboken,
N. J., a corporation of New Jersey

Application June 3, 1941, Serial No. 396,401

10 Claims. (Cl. 216—57)

The invention relates to labeling machines and has for its object to provide such machines with a labeling mechanism constructed and operating in a novel manner to apply labels or their equivalent to moving articles without interference with the movement thereof.

The invention contemplates further the provision of a novel labeling mechanism arranged to apply labels or their equivalent to traveling webs of materials at spaced intervals without arresting the travel of said webs.

Other objects will appear from the description hereinafter and the features of novelty will be pointed out in the claims.

In the accompanying drawings, which illustrate an example of the invention without defining its limits,

Fig. 1 is a fragmentary sectional elevation of a labeling machine in which the novel features are embodied;

Fig. 2 is a fragmentary front elevation of the machine;

Fig. 3 is a fragmentary plan view partly in section, and

Fig. 4 is a detail perspective view showing label supporting means included in the novel mechanism.

The labeling machine selected for the purpose of illustrating and describing the novel mechanism is of the type shown in my United States Patent No. 2,227,816, of January 7, 1941, and includes an upright supporting frame 10 on which a suitable container or hopper 11 is mounted in position for proper co-operation with the associated elements of the machine. The container or hopper 11 contains a supply of labels 12 in the form of an upright supply stack from the upper end of which the terminal labels are successively removed for application to the articles for which said labels are intended. Suitable provision is made, in any customary manner, for periodically restoring the upper end of the stack of labels 12 to a predetermined level in proper operative relation to the co-operating elements of the machine. The elevating mechanism 13 whereby this periodical adjustment is effected does not per se constitute a novel feature of the labeling machine, and may for instance be of the type shown in my patent hereinbefore mentioned, and in the same way may include a feeler 14 and associated elements operating to control the aforesaid elevating mechanism.

In the labeling machine as illustrated, the means whereby individual labels 12 are successively removed from the stack and transferred

therefrom to the point of application for application to the elements to be labeled, is of the suction operated type, and per se may be of any suitable construction. As shown, the label transferring means consists of a carriage 15 slidably mounted upon a horizontal guide rail 16 supported on the frame 10 in any convenient manner. The carriage 15 is slidably reciprocated in the rail 16, for instance, by means of an arm 17 fixed upon a shaft 18 and having its free end pivotally connected with a coupling rod 19 which in turn is yieldingly and pivotally connected at 20 with a lug 21 forming part of or fixed upon the carriage 15 as shown in Fig. 1.

In the operation of the machine, the carriage 15 is reciprocated on the rail 16 by rocking the shaft 18 which swings the lever 17 to alternately push and pull the carriage 15 lengthwise of the rail 16. The mechanism whereby said shaft 18 is rocked may be the same as in my previously mentioned patent and needs no further description herein as per se it forms no part of the instant invention.

The carriage 15 serves as a support for a member 22 which is vertically slidable on said carriage 15 and at its lower end carries a suction head 23. The specific construction of the latter may be of any conventional type, the suction head 23 in any event being connected with a source of suction, for instance, by means of a suitable tube 24. Throughout the major portion of the reciprocation of the carriage 15 the member 22 and with it the suction head 23 is held against downward vertical movement by means of a roller 25 which travels lengthwise of a fixed rail 26, the latter at predetermined points being recessed to permit downward vertical movement of the member 22 and suction head 23 in the same way as in my prior patent referred to above. This enables the suction head 23 to be operated to remove terminal labels 12 from the upper end of the supply stack and to deposit said labels in label applying position at the point of application as will be herein-after more fully set forth. The aforesaid vertical movements of the member 22 and suction head 23 may be effected by means of any suitable mechanism such as for instance shown and described in my previously mentioned patent.

In the labeling machine illustrated in the drawings, the labels 12 picked up successively by the suction head 23 from the supply stack are provided with a coating of adhesive on one surface during the transfer of said labels 12 from the supply stack to the point of application. For this purpose each label subsequent to its removal

from the supply stack by the suction head 23 is carried thereby into progressive tangential adhesive receiving relation with the adhesive applying roll 27 of the adhesive applying means 28 suitably mounted in proper position in the machine as shown for instance in Fig. 1. The adhesive applying means may be of any suitable construction and may correspond to that of my previously mentioned patent and accordingly requires no further description as per se it does not constitute a novel feature of the instant labeling machine.

The novel mechanism embodied in the instant labeling machine includes supporting means located at the point of application on which the successive labels 12 are temporarily deposited in proper applying relation to the moving article to which said labels are to be applied. In the illustrated example this supporting means comprises supporting members or bars 29 extending in horizontal directions and spaced apart to a predetermined extent dependent upon the dimensions of the labels 12 which are being applied by the mechanism; the arrangement is such that the labels 12 will span the space between the members 29 with the opposite ends of said labels in temporary adhesive connection with said members after the deposit of said labels 12 thereon by the suction head 23 has taken place. The members 29 are carried by a supporting bar 30 of suitable type which may be mounted in the machine in any convenient manner as by means of a bracket 31 as illustrated more or less diagrammatically in Fig. 2 of the drawings.

A plunger or slide 32 is slidably mounted in a vertical guide 33 suitably supported in the machine in proper operative relation to the label applying point and to the supporting members 29. The plunger or slide 32 may be vertically actuated in the guide 33 in any convenient manner as by means of a lever 34 loosely mounted on the shaft 18 and pivotally connected with the plunger or slide 32 in any convenient manner as by being provided with a rounded front end 35 projecting into a slot formed in the plunger or slide 32. The lever 34 may be rocked on the shaft by mechanism similar to that shown in my patent referred to hereinbefore and including an operating member 36 pivotally and adjustably connected at 37 with the lever 34 and actuated in the intended manner by means of mechanism similar to the means whereby the lever which actuates the pressure plunger in my previously mentioned patent is operated. The plunger or slide 32 at its lower end carries means for removing the labels 12 from the supporting members 29 and applying them to the articles for which they are intended. As the novel labeling mechanism is designed primarily for applying labels to moving articles, the aforesaid applying means is constructed to properly co-operate with said moving articles in the application of the labels 12 thereto. In the specific form illustrated in the drawings, the applying means comprises an endless belt 38 of suitable material and dimension transversely in dependence upon the dimensions of the labels 12 with which said belt 38 is designed to operate. The belt 38 is carried by pulleys 39 and 40 rotatably mounted in spaced relation on a lever 41 pivoted at 42 on a transverse projection forming part of the slide or plunger 32 as shown in Fig. 2 of the drawings; in the preferred arrangement the pivot 42 of the lever 41 is in registry with the axis of the pulley 40. An arm 43 extends at an upward inclination from the lever 41 preferably

as an integral part thereof and is provided at its free end with an apertured projection 44 with which one end of a spring 45 is connected; the other end of said spring is attached at 46 to the slide or plunger 32. The arm 43 preferably is further provided with a stop shoulder 47 arranged to co-operate with a suitable stop 48 on the slide or plunger 32 to arrest the pivotal movements of the arm 43 and lever 41 in one direction for the purpose to be more fully set forth hereinafter. The stop 48 is illustrated in the form of a stop screw adjustably mounted in a lug 49 carried by the slide or plunger 32 and fixed in an adjusted position for instance by means of a lock nut 50. The arrangement is such that the belt 38 and its associated elements are located above and in vertical registry with the space between the label supporting members 29 as illustrated in Figs. 2 and 3.

20 In the illustrated example the labeling mechanism is shown in a form designed primarily for applying labels at spaced intervals to travelling webs of material as exemplified for instance by travelling lengths of linoleum or the like 51. 25 The run of the web of linoleum 51 or other material which is to receive the labels in such case travels over a suitable support 52 in label receiving relation to the label supporting means or specifically the label supporting means 29, as 30 illustrated in Fig. 2, it being understood that the web of linoleum 51 or its equivalent may be operated in a manner to travel over the support 52 by any suitable and conventional means. The machine further may include means for completing the application of the labels which means may be of any suitable nature and is illustrated in the form of a pressure roller 53 carried by a shaft 54 rotatably mounted in bearing blocks 55 and rotatably operated by means of a belt 56 and 40 co-operating pulley 57 mounted on the shaft 54. The bearing blocks 55 are slidably mounted in upright bearing guides 58 suitably fixed in place, for instance, upon the support 52. A yielding pressure is developed on the roller 53 by means 45 of springs 59 which bear with one end against the bearing blocks 55 and with their other ends engage disks 60 adjustably mounted on said upright bearing guides 58 by means of screws 61 fixed against unintentional rotation by means 50 of lock nuts 52.

In practice, during an operative period of the machine, the web 51 of linoleum or other material will be progressively and uninterruptedly advanced on the support 52 at a predetermined speed of travel and successive terminal labels 12 will be removed from the supply stack by the suction head 23 and deposited upon the supporting members or bars 29 with the opposite end portions of said labels 12 in temporary adhesive contact with said members 29 as illustrated in Fig. 4.

The arrangement is such that the web 51 will pass beneath and in label receiving proximity to the supporting members 29 and the labels 12 thereon as shown in Fig. 2. It will be understood that the slide or plunger 32 and the belt 38 and associated elements carried by said slide or plunger occupy a raised position during the operation of depositing a label 12 upon the supporting members 29 by the suction head 23 or its equivalent. After a label 12 has been deposited on the supporting members 29, the machine will operate to return the suction head and its co-operating elements back toward the supply

stack of labels 12 ready for the next operative cycle. In proper operative synchronism the lever 34 will be rocked downwardly to correspondingly move the slide or plunger 32 downwardly in the guide 33. At this stage the stop 47 of the arm 43 will be held in contact with the stop screw 48 of the slide or plunger 32 by the action of the spring 45 so that the lever 41 and belt 38 will occupy a downwardly inclined position as the slide or plunger 32 descends in the guide 33. This downward movement of the slide or plunger 32 will finally bring that part of the belt 38 which travels over the pulley 39 into contact with the upper surface of the travelling web 51 of linoleum or other material. As the downward movement of the parts continues the lever 41 and belt 38 will be rocked on the pivot 42 against the tension of the spring 45 and will bring the belt 38 into engagement with the edge of the label 12 supported on the members 29. As this occurs, the frictional engagement between the belt 38 and web 51 will gradually cause the belt 38 to travel on the pulleys 39 and 40 at a speed corresponding to the speed of travel of the web 31. It will be noted, as shown in Fig. 2, that the lower run of the belt 38 at this stage is in engagement under the tension of the spring 45, with the outer edge of the label 12 located at the outer ends of the supporting members 29. As a result of this, the lower run of the belt 38 which travels in the same direction as the advancing web 51 will withdraw the label 12 from the supporting members 29 as the speed of the belt 38 coincides with the speed of travel of the web 51. This withdrawal of the label 12 from the supporting members 29 by the belt 38 is possible because the adhesive whereby the opposite ends of the label 12 are temporarily secured upon the supporting members 29, is still tacky and has not yet had time to become set.

As the label 12 is thus progressively withdrawn from the supporting members 29, said label will be carried along by the belt 38 to finally have its adhesive coated surface brought into engagement with the travelling web 51. As the operations continue the label 12 will pass between the belt 38 and the web 51 and will be pressed into engagement therewith by the action of the spring 45 so that said label 12 will be adhesively applied to the surface of the web 51. The application of the label 12 to the web 51 will be completed as the applied label 12 is carried by the web 51 beneath the pressure roller 53 or its equivalent; in some cases, this final pressure to complete the application of the label may be omitted. After a label 12 has been completely withdrawn from the supporting members 29 and applied to the web 51 by the belt 38, the lever 34 will be rocked in an upward direction in proper timing, to correspondingly raise the slide or plunger 32 in the guide 33. As this occurs, the pulley 40 and the adjacent sections of the belt 38 will move upwardly away from the supporting members 29 and the spring 45 will progressively rock the arm 43 and lever 41 on the pivot 42 until the stop 47 engages the stop screw 48 to thereby arrest said pivotal movement. The position of the parts are thereby fixed as the elevation of the slide or plunger 32 and associated elements continue until this final upward position has been reached whereupon the cycle of operations described above is repeated. As a result successive labels 12 will be applied and affixed to the web 51 at spaced intervals deter-

mined by the speed of travel of the web 51 or its equivalent and the operative adjustment and timing of the machine and the applying mechanism.

5 In addition to functioning as mechanism for applying labels at spaced intervals to travelling webs of material, the mechanism may be used with equal efficiency for applying labels to articles such as packages of merchandise moving over a given path in spaced relation and reaching the application point at successive intervals. The mechanism is simple in construction and efficient in operation and requires no particularly expert supervision and in addition may, if desired, be readily incorporated in existing labeling machines.

10 Various changes in the specific forms shown and described may be made within the scope of the claims without departing from the spirit of the invention.

15 I claim:

1. In a labeling machine for applying labels to moving articles, stationary supporting means for supporting labels in a stationary applying position at the point of application, a labeling mechanism including an applying member arranged to move in corresponding direction and at corresponding speed with said articles for removing said labels from said supporting means and applying said labels to said articles without interruption of the movement thereof.

2. In a labeling machine for applying labels to traveling webs of material at spaced intervals, a movable applying member normally out of contact with the movable web, and means for periodically shifting said applying member into contact with said traveling web of material whereby said applying member is operated in corresponding direction and at corresponding speed with said web of material to apply labels thereto at spaced intervals.

3. In a labeling machine for applying labels to moving articles, supporting means for supporting a label in a stationary applying position at the point of application, and a labeling mechanism including an applying member arranged to move in corresponding direction and at corresponding speed with a moving article for removing said label from said supporting means and applying said label to said article without interruption of the movement thereof.

4. In a labeling machine for applying labels to moving articles, supporting means for supporting a label in a stationary applying position at the point of application, means for depositing a label upon said supporting means in said stationary applying position, and a labeling mechanism including an applying member controlled by the moving article for removing the label from said supporting means and applying said label to said article without interruption of the movement thereof.

5. In a labeling machine for applying labels to traveling webs of material, supporting means for supporting a label in applying position at the point of application, a movable carrier, a movable applying member mounted on said carrier, and means for adjusting said carrier to shift said applying member into contact with a traveling web of material whereby said applying member is operated in speed synchronism with said traveling web for applying a label thereto without interruption of the travel of said web.

6. In a labeling machine for applying labels at spaced intervals to traveling webs of material, supporting members located in spaced relation to

each other for supporting individual labels in applying relation to a traveling web of material, a movable slide mounted in operative relation to said supporting members, a movable applying member carried by said slide, and means for periodically operating said slide to shift said movable applying member into operative relation to the traveling web and to the label on said supporting members whereby said label is removed from the latter and applied to said web of material at spaced intervals without interruption of the travel thereof.

7. In a labeling machine for applying labels at spaced intervals to traveling webs of material, supporting members located in spaced relation to each other for supporting individual labels in applying relation to a traveling web of material, a movable slide mounted in operative relation to said supporting members, an endless applying member movably carried by said slide, and means for periodically operating said slide to shift said applying member into contact with said traveling web and with the label on said supporting members whereby the endless applying member is operated in speed synchronism with said traveling web to remove the labels from said supporting members and applied to said web of material at spaced intervals without interruption of the travel thereof.

8. In a labeling machine for adhesively applying labels to traveling webs of material at spaced intervals, a container for a supply of labels, supporting members in spaced relation to each other at the labeling point, adhesive applying means between said container and said labeling point, means for transferring labels from said supply

and depositing said labels on said supporting members in temporary adhesive connection therewith, a vertically operable slide in operative relation to said supporting members, a movable endless label applying belt carried by said slide, and means for periodically operating said slide to shift said applying belt into engagement with the supported label and with the travelling web whereby the latter operates said belt to withdraw the labels from said supporting members and apply said label to the web at spaced intervals without interruption of the travel of said web of material.

9. In a labeling machine, a labeling mechanism for applying labels to moving articles comprising an applying member normally occupying an inoperative label applying position relatively to a moving article and movable into label applying relation therewith and operating in the same direction and at the same speed as said moving article to apply a label thereto without interruption of the movement of said article.

10. In a labeling machine, a labeling mechanism for applying labels to moving articles comprising a movable slide, a lever pivotally mounted on said slide, pulleys loosely mounted on said lever, an endless label applying belt on said pulleys, an arm connected with said lever, a spring acting on said arm to press said applying belt into engagement with said articles for applying labels thereto without interruption of the movement of said articles, and co-operating stops on the slide and arm respectively for maintaining the lever and associated belt in a normal inoperative position on said slide.

GEORGE W. VON HOFF.
